WINDOW CONSTRUCTION

Olien Polson and Theodore John Nelson,
Chicago, Ill.

Application September 7, 1950, Serial No. 183,538

4 Claims. (Cl. 20—49)

1 The present invention relates generally to the construction of sliding sash windows and more specifically to certain improvements in a window of the general type disclosed in our copending application Serial No. 785,262, filed November 12, 1947.

One object of the invention is to provide a window having a novel sash mounting and positioning arrangement permitting vertical sliding movement of either or both sashes as well as vertical swinging movement for purposes of ventilation and cleaning.

Another object is to provide a window construction having an improved interlock means which precludes vertical sliding movement of the sash while permitting vertical swinging movement of the same.

A further object is to provide a window of the character set forth and wherein the novel interlock means is adapted to afford protection against unauthorized opening of the window by sliding the sash vertically or pushing the same inwardly.

Still another object of the invention is to provide a window construction of the above type and which will readily permit the installation of a storm window or screen from the interior of the room in which the window is located.

Other objects and advantages will become apparent as the following description proceeds, taken in connection with the accompanying drawings, wherein:

Figure 1 is a fragmentary perspective view of an illustrative window embodying the present invention, certain parts of the window having been omitted for purposes of clearer illustration.

Fig. 2 is an enlarged fragmentary perspective view detailing one of the sash carriers and its associated latching means.

Fig. 3 is an enlarged fragmentary perspective view showing a sash in a fully locked or burglar-proof condition.

Fig. 4 is an enlarged fragmentary transverse sectional view taken horizontally through the window of Fig. 1 and in the plane of the line 4—4.

Fig. 5 is a vertical sectional view taken through the head jamb and sill of the window of Fig. 1 and showing in elevation the sashes and certain parts associated therewith.

Fig. 6 is an enlarged vertical sectional view taken through a guide bar and the motion arresting device associated therewith.

Fig. 7 is an enlarged fragmentary perspective view detailing the relation between one of the latching members and one of the front guiding strips in the window of Fig. 1.

2 While the invention is susceptible of various modifications and alternative constructions, a preferred embodiment has been shown in the drawings and will be described below in considerable detail. It should be understood, however, that there is no intention to limit the invention to the specific form disclosed, but on the contrary, the intention is to cover all modifications and alternative constructions falling within the spirit and scope of the invention as expressed in the appended claims.

Referring more specifically to the drawings, there is shown in Figs. 1 and 5 an illustrative window 10 embodying the present invention. The window 10 is built within a generally rectangular frame 11 comprising the usual parallel side members or jambs 12 spanned at the top and bottom respectively by a head jamb 14 and a sill 15. Mounted for vertical sliding movement in the frame 11 are glazed upper and lower sashes 16, 18, each of rectangular form and having side rails 19 connected at their extremities by top and bottom rails 20 and 21. Also mounted in the frame 11 but located outwardly of the upper and lower sashes 16, 18 is a storm sash or screen 22 of somewhat narrower width than the other sashes so as to permit its installation from the interior of the room in which the window 10 is located.

For the purpose of permitting both vertical sliding and inward swinging movement, each of the sashes 16, 18 is pivotally attached to an individual pair of sash carriers 24, the point of pivotal attachment 25 between each carrier and its associated sash being located preferably adjacent the lower ends of the side rails 19. In the present instance, each of the sash carriers 24 is of generally J-shaped cross section and is adapted to interfit snugly with a T-shaped piece of weather-stripping 26 fixed to the side rail 19 of each sash. The sash carriers 24 are confined within the frame 11 but permitted vertical sliding movement relative thereto by means of front and rear guiding strips 28, 29 (see Fig. 4) arranged in pairs along the inside face of either side panel 12. There may also be interposed between the side panels 12 and the guiding strips 28, 29 a formed sheet metal liner 30. As clearly shown in the drawing, each of the guiding strips 28, 29 is slotted longitudinally to accommodate the J-shaped cross section of the sash carriers 24 and to constrain the same against substantially all other movement except vertical sliding movement, or in other words, movement parallel to the general plane of the frame 11. In order to enable the upper sash 16 to be swung inwardly without in-

terference, the sash 16 is made in this instance with a somewhat smaller lateral dimension than the sash 18. Consequently, the front guiding strip 28 is somewhat thinner than the rear guiding strip 29 so as to compensate for this dimensional difference.

Provision is made for releasably locking each sash against angular movement about the pivot points 25 in a simple yet effective manner. This is accomplished by the use of one or more latches 31 each susceptible of locking engagement with the upper portion of one of the sashes and the guiding strip associated therewith. Since the latches 31 are substantially identical, a detailed description of one, together with the parts of the window associated therewith, will suffice for all. Accordingly, reference will be made to the latch 31 associated with the lower sash 18 and located on the right-hand side of the latter (as viewed in Figs. 1, 3 and 4). The latch 31 in this instance is fashioned in the form of a short metal bar pivoted to an outstruck lug 32 on the sash carrier 24 as by means of a rivet 34, the guiding strip 28 being provided with a longitudinally extending latch channel 35 to receive the lug 34 and the pivoted end of the latch. By reason of this structure, the latch 31 is swingable between a raised or upright position illustrated in Figs. 3 and 7 and a lowered position illustrated in Figs. 2 and 4. Adjacent the upper end of its side rail 19, 30 the sash 18 is notched out to define a latch stop 36. Thus when the latch 31 is in its lowered position and an attempt is made to swing the sash inwardly about the pivot points 25, the latch stop 36 is immediately accosted by the latch 31 to preclude such movement.

Provision is also made for interlocking the sash 18 and its carriers 24 against vertical sliding movement as an incident to shifting the latch 31 from lowered to raised position to release the sash 18 for inward swinging movement. This is accomplished by effecting positive engagement between the latch 31 and the guiding strip 28 when the latch is in its upright position. In furtherance of such objective, the latch 31 is provided with a locking pin 38 projecting outwardly therefrom. To receive the pin 38, the guiding strip is formed with a notch 39 which opens into the latch channel 35. For safety purposes, the top and bottom walls of the notch 39 are undercut, the notch in this instance having a substantially dovetailed profile (see Fig. 7). Once the locking pin 38 enters the notch 39, any attempt to move the sash vertically simply cams the pin 38 into deeper engagement with the notch 39 and accidental disengagement of the latch 31 is entirely prevented. In order to permit the latch to be shifted from its upright position to its lowered position, the free end of the latch is preferably formed with a dull point which is readily engageable by the finger. To further facilitate handling of the latch 31, the surrounding portion of the guiding strip 28 is cut away to define a finger notch 40.

When two of the latches 31 are mounted on 65 the carriers for the sash 18 in the manner described above, an effective burglar-proof locking arrangement is readily obtained by placing one latch in raised position and the other in lowered position. In this condition, the upright 70 latch locks the window against vertical movement and if the notches 39 and 40 are judiciously located, the possibility of having an unauthorized person reach in from the outside and release the latch is eliminated regardless of whether the 75

sash is maintained in a closed or slightly opened condition. The lowered one of the latches 31 of course locks the sash 18 against inward swinging movement. When both of the latches 31 are down or in their lowered position, free vertical sliding movement of the sash 18 is permitted. Conversely, when both of the latches 31 are in their raised position, free inward swinging movement of the sash 18 is permitted.

In the foregoing description of the latching arrangement, reference has been made only to the lower sash 18 rather than the upper sash 16. The latter is constructed in a similar manner, the latches 31 being mounted near the tops of the sash carriers 24 and the guiding strips 29 being formed with latching channels 35 and one or more locking pin and finger notches (not shown) similar to the notches 39, 40. Instead of the upstanding latch stops 36, however, the upper sash has the latches 31 recessed in its top rail, the rear wall of the recess serving as a latch stop. To permit lifting of the latches 31 to raised position, the top rail of the upper sash 16 has finger notches 41 at the ends of the latch recesses.

For the purpose of yieldably positioning the lower sash 18 both vertically and angularly, a common frictional motion arresting means is utilized. While such means may be either singular or plural, the latter is preferable and will presently be described. Accordingly, there are mounted adjacent the intersection of the head jamb 14 with the two side jambs 12 a pair of anchor fittings 42. Pivoted upon respective ones of the latter and swingable in a generally vertical plane are a pair of guide bars 44. Each of the latter is adapted to telescope into a motion arrester 45 of the general type disclosed in our co-pending application Serial No. 785,262, supra. For present purposes, it might be noted that the motion arrester 45 is of the ball and inclined wedge type, being adapted to yieldably resist relative motion in either direction between the guide bar 44 and the arrester housing 46. The extent of this yieldable resistance can be varied as by means of adjusting screws 48. In the present instance, each motion arrester housing 46 has fixed thereto a lug 49 which is pivotally attached as at 50 to the weatherstripping 26 of the sash 18. By reason of the foregoing structure, it will be perceived that relative sliding movement between the guide bar 44 and the motion arrester 45 can take place regardless of whether the sash 18 is being slid vertically or, on the other hand, is being rocked inwardly about the pivot points 25. By proper adjustment of the arrester 45, the frictional resistance of the same may be regulated sufficiently to allow easy positioning of the sash 18 vertically or angularly at any desired point.

For the purpose of counterbalancing the sash 18 in both the vertical and angular directions, the window 10 is provided with at least one and preferably a pair of tensile springs 51. Each of the latter is interposed between one of the pivot points 50 on the sash weatherstripping 26 and a stud 52 fixed either to a corresponding one of the anchor fittings 42 or the upper end portion of one of the guide bars 44. The springs 51 are respectively housed within recesses 54 each defined by one of the side jambs 12, the front guiding strip 28, and the weatherstripping 26 of the sash 18. Thus when the sash 18 is in its upright or vertical condition, the guide bar 44 is also housed within the recess 54 in overlying relation with the spring 51 so as to conceal the same. In the present instance, the upper sash 16 is provided with

a pair of counterbalancing tensile springs 55 similar to those utilized for the lower sash 18. The guide bars 44 and motion arresters 45 are, however, preferably eliminated because the upper sash is customarily allowed to remain vertical and closed except when being cleaned. Under normal usage of the window 10, practically all the vertical and angular adjustment for ventilation is done by manipulation of the lower sash 18. The upper sash is, however, susceptible of angular movement in the event that it has to be cleaned.

We claim as our invention:

1. In a window structure, the combination of a generally rectangular frame, a pair of sash carriers slidable along the general plane of said frame, a sash pivoted on the lower end portions of said carriers for angular movement relative thereto, said sash also being susceptible of sliding movement with said carriers along the general plane of said frame, a latch pivoted on one of said carriers adjacent the upper end thereof and manually shiftable between a raised position and a lowered position, a latch stop fixed to the upper end of said sash and susceptible of abutment with said latch when in lowered position, a locking pin fixed to said latch, and a pair of guiding strips mounted inside said frame along the sides thereof, each of said guiding strips being susceptible of slidably receiving a respective one of said carriers, one of said guiding strips being provided with a longitudinal latch channel for the reception of said latch in raised position, said one guiding strip also being provided with an undercut notch for reception of said locking pin when said latch is in raised position.

2. In a window structure having a generally rectangular frame, the combination comprising a pair of slidable sash carriers, a sash bodily slidable with said carriers, pivotal connections between the lower lateral edge portions of said sash and the lower end portions of said carriers, a pair of latches each pivoted on the upper end portion of a respective one of said carriers for movement substantially parallel to the general plane of said frame, each of said latches being shiftable between a first and a second position, a pair of latch stops fixed to said sash adjacent the upper lateral extremities thereof and susceptible of abutting engagement with said latches when the latter are in said first position, a locking pin fixed to each of said latches, and a pair of guiding strips mounted inside the frame along the sides thereof, each of said guiding strips being susceptible of slidably receiving a respective one of said carriers, each of said guiding strips being provided with a longitudinal latch channel for the reception of one of said latches in said second position, each of said guiding strips also being provided with an undercut notch for the reception of said locking pin and a finger notch spaced from said undercut notch to permit manual release of said latch from said second position.

3. In a sliding and swinging window sash structure having a generally rectangular frame, the combination comprising a vertically slidable sash, a pair of sash carriers, guiding strips

mounted on opposite inside faces of the frame, said guiding strips and said sash defining an upright recess on either side of said frame adjacent the front edges thereof, said guiding strips also being susceptible of slidably receiving said sash carriers, means including a pair of pivotal connections interposed between the lower end portion of each of said sash carriers and the lower lateral extremities of said sash, a counterbalancing tensile spring housed within said upright recess and connected between the upper portion of said frame and an abutment on one of the lateral edges of said sash spaced from one of said pivotal connections, a frictional motion arrester also pivotally connected to said sash by means of said abutment, and a swingable guide bar interposed between the upper end of said frame and said motion arrester, said guide bar being slidable through and engageable with said frictional motion arrester, said guide bar also being housed within said upright recess and in overlying relation with respect to said spring.

4. In a sliding and swinging window sash structure having a generally rectangular upright frame, the combination comprising a vertically slidable sash, guiding strips mounted on opposite inside faces of the frame, said guiding strips and said sash defining upright recesses on either side of said frame adjacent the front edges thereof, a pair of sash carriers longitudinally slidable relative to said guiding strips, a pivotal connection interposed between the lower end portion of each of said sash carriers and the respective lower lateral extremities of said sash, anchor fittings at the top of said frame, a pair of tensile springs each housed within a respective one of said recesses and connected respectively between said anchor fittings at the top of said frame and abutments on the lateral edges of said sash spaced above said pivotal connections, a pair of frictional motion arresting devices pivotally connected to said sash by means of said abutments, guide bars interposed between respective ones of said anchor fittings and said motion arresting devices, said guide bars being telescopically slidable through and within their associated motion arresting devices, said guide bars being housed within respective ones of said recesses and in overlying relation with respect to said tensile springs.

OLIEN POLSON,
THEODORE JOHN NELSON.
